UNITED STATES PATENT OFFICE.

IVAR A. RANDEL, OF CHICAGO, ILLINOIS, ASSIGNOR TO McCORD AND COMPANY, OF CHICAGO, ILLINOIS, A CORPORATION OF NEW JERSEY

JOURNAL-BOX.

1,077,159.

Specification of Letters Patent. Patented Oct. 28, 1913.

Application filed May 17, 1913. Serial No. 768,245.

To all whom it may concern:

Be it known that I, IVAR A. RANDEL, a citizen of the United States, residing at Chicago, in the county of Cook and State of Illinois, have invented certain new and useful Improvements in Journal-Boxes; and I do hereby declare the following to be a full, clear, and exact description of the invention, such as will enable others skilled in the art to which it appertains to make and use the same.

My invention relates to journal boxes and provides an improved journal box comprising an independently formed metallic cellar and a top made fast to the cellar in the forming of the top.

The improved journal box, as preferably constructed, has a pressed steel cellar and cast steel top. The demands of the railway service have indicated that this is a type of journal box very much desired, and many experiments have been made with a view of obtaining a satisfactory connection between the body and top of such a box. For instance, it has hitherto been proposed to secure a pressed steel cellar to a cast top by bolts or rivets. Such construction, however, has been found to be far from satisfactory, because, in the first place, it is expensive, and in the second place, it does not give a tight or solid joint uniting the elements of the box, nor does it become practically an integral structure. Furthermore, the pressed steel cellar is usually made of two or more elements, either the inside or outside dust guard wall being constructed separately from the body of the cellar, which complicates and makes more difficult proper connection of the elements of the box, either by bolts or rivets.

In accordance with my improved process, a pressed steel cellar is placed in or associated with the mold and the cast steel top is cast onto the upper edge thereof. Preferably, the pressed steel cellar has an integral pressed steel outside dust guard and an independently constructed pressed steel inside dust guard wall; and these two elements of the cellar are properly assembled and so located in a mold or so associated with a mold that the cast steel top will be cast onto the upper edges of the body of the cellar and onto the upper edges of both the outside and inside dust guard walls. Thus,

by the act of casting the top, all of the elements of the journal box are rigidly united with a very tight and strong joint, which, in effect, integrally unites the elements of the box. To further insure a strong tight joint between the pressed steel and cast elements of the box, the upper edge of the cellar, and the inside and outside dust guard walls, are perforated, upset, punch-marked or folded over, so as to form positive interlocking joints with the cast steel top. The cast steel run in to form the top will be so hot that it will fuse the pressed steel elements of the box to some extent, and further insure a very tight and substantially integral joint. Furthermore, the shrinkage of the cast steel top about the upper edges of the cellar produces a very strong bond between the parts, which is materially increased by the cross connections between the cellar and the top, afforded by the openings, recesses, or enlargements in the upper edges of the cellar, which are engaged by the cast metal of the top. This shrinkage bond between the cast steel top and the sheet steel cellar possesses great inherent strength and is an important factor in maintaining an intimate union between the top and cellar under the most severe condition of practical operation.

In the accompanying drawings which illustrate the invention, like characters indicate like parts throughout the several views.

Referring to the drawings: Figures 1, 2 and 3 are perspective views showing, respectively, the top, the pressed steel cellar, and the pressed steel inside dust guard wall of the box, the said elements being separated to better illustrate the forms thereof; Fig. 4 is a vertical section taken through the completed journal box on the line $x^4 x^4$ on Fig. 5; Fig. 5 is a plan view of the completed journal box with some parts sectioned on the line $x^5 x^5$ on Fig. 4; and Fig. 6 is an outer end elevation of the completed box, with some parts sectioned on the line $x^6 x^6$ on Fig. 4.

The pressed steel cellar 1 is, as indicated, formed with an integral outside dust guard wall 2, and is provided with a separately constructed inside dust guard wall 3 which is a rectangular structure, preferably having at its upper edge an overturned flange 4 formed with perforations 5. The

upper edge of the cellar 1 is provided with perforations 6, and the upper edge of the outside dust guard wall 2 is formed with perforations 7. At the proper distance from 5 its outside dust guard wall 2, the cellar 1 is formed in its side walls with vertical offset ledges 8, against which the vertical edges of the inside dust guard wall 3 are placed. Also, the bottom of the cellar is shown as 10 provided with a transverse depression or channel 9 that receives the lower edge of the inside dust guard wall 3. The side walls of the cellar 1 are also provided with vertical corrugations 10 which stiffen the said side 15 walls. The central inwardly pressed corrugations 10 afford clearance for the usual arch bar bolts, not shown.

The cast steel top 11 has the usual features necessary to make the journal box, 20 when completed, interchangeable with any other journal box of the "Master Car standard." For instance, it has lid hinge lugs 12, wedge front stops 13, journal bearing side stops 14, arch bar seats 15, arch 25 bar bolt holes 16 and dust guard slot 17. It will, of course, be understood, that the cast top 11 will never appear separately, as shown in Fig. 1, for the reason that it is cast directly onto the pressed cellar.

30 As already indicated, the inside dust guard wall 3 is placed in proper position within the cellar, to-wit, against the ledge 8 and resting on the channel 9, and then its upper edge is placed within the mold, and 35 the top 11 is cast thereon, as already fully stated. The metal which runs through the perforations 5, 6 and 7 very firmly interlocks and cross connects the cast top to the pressed steel elements of the box. The upper 40 set edge or flanged edge, or otherwise roughened or irregular surface, would have more or less the same effect, but the perforations give the very best possible kind of an interlocking action. Pressed steel 45 makes the best material for the body of the cellar and cast steel for the top, but the cellar might be made of other pressed sheet metal and the top from other cast metal, all within the broad scope of the invention 50 herein disclosed and claimed.

While the mode of effecting the joint between the cellar and the top has been described as casting the top on to and fast to the upper edge of the cellar, it is to be 55 understood that the invention also contemplates the making of the shrinkage joint between the cellar and the top, in the forming of the top, by any equivalent mode of procedure; for in any method of forming 60 the top, it would be necessary to bring the metal up to a very high temperature and

a corresponding cooling shrinkage would occur.

What I claim is:

1. A journal box comprising an independently formed metallic cellar and a top made fast to the cellar by the metal of the top in the forming thereof. 65

2. A journal box comprising an independently formed metallic cellar and a top 70 of cast metal cast fast to said cellar.

3. A journal box comprising an independently formed metallic cellar and a top 75 of cast steel incasing the upper edges of said cellar and cast fast thereto.

4. A journal box comprising an independently formed metallic cellar and a cast steel top, said cellar and top having interlocking parts made fast with each other in the casting of the top. 80

5. A journal box comprising an independently formed metallic cellar, an independently formed metallic dust guard wall and a metal top made fast to said cellar and dust guard wall in the forming of the 85 top.

6. A journal box comprising an independently formed metallic cellar, an independently formed dust guard wall and a cast metal top, said cellar, dust guard wall 90 and top having interlocking parts made fast with each other in the casting of the top.

7. A journal box comprising an independently formed metallic cellar and a top of cast metal cast onto and incasing the 95 upper edge of the cellar and having its vertical incasing surfaces cross-connected by the metal of the top to increase the shrinkage bond on the cellar.

8. A journal box comprising an independently formed metallic cellar and cast metal forming a complete top to the cellar, 100 and cast fast thereto.

9. A journal box comprising an independently formed metallic cellar and cast 105 metal forming a complete top to the cellar, following the upper marginal edges of the side and back walls of the cellar, and which top is cast fast to the cellar.

10. A journal box comprising an independently formed metallic cellar and a top of cast metal cast onto and increasing the upper edge of the cellar the incased edge 110 having perforations therein through which the metal of the top passes to form cross- 115 connections.

In testimony whereof I affix my signature in presence of two witnesses.

IVAR A. RANDAL.

W. J. SCHLACKS,
R. S. MCINTOSH.

Corrections in Letters Patent No. 1,077,159.

It is hereby certified that in Letters Patent No. 1,077,159, granted October, 28, 1913, upon the application of Ivar A. Randel, of Chicago, Illinois, for an improvement in "Journal-Boxes," errors appear in the printed specification requiring correction as follows: Page 2, lines 74 and 95, for the word "incasing" read *encasing*; same page line 112, for the word "increasing" read *encasing*; and line 113, for the word "incased" read *encased*; and that the said Letters Patent should be read with these corrections therein that the same may conform to the record of the case in the Patent Office.

Signed and sealed this 24th day of February, A. D., 1914.

[SEAL.]

J. T. NEWTON,
Acting Commissioner of Patents.
